UNITED STATES PATENT OFFICE

2,560,837

ROLLER MILL WITH PIVOTED ROLL SUPPORT

Charles J. Alciati and Arthur J. Andersen, San Francisco, Calif., assignors to Moore Dry Dock Company, Oakland, Calif., a corporation of California

Application October 6, 1947, Serial No. 778,246

2 Claims. (Cl. 241—232)

1

This invention relates to grinding mills and particularly to a grinding mill that is suitable for grinding coffee, seeds, spices, etc. in which conventional steel rolls are employed for performing the work.

One of the objects of the invention is the provision of a mill provided with means for quickly adjusting the rolls from outside the mill to precise and accurate spacing thereof so as to enable the accurate grinding of material to the desired fineness.

Another object of the invention is the provision of a mill in which trammimg of the rolls is more easily and quickly accomplished than heretofore.

An additional object of the invention is the provision of a mill having improved means for setting the rolls with equal yieldable tension thereon including bell cranks and coil springs operatively connected with one of the arms of the cranks.

A still further object of the invention is the provision of a mill that is easily and quickly opened up for any replacements or for examination, and that is as easily reassembled, and which mill is self cleaning by reason of the elimination of ledges and the like that tend to accumulate material.

Another object is the provision of structure in a mill that enables the quick assembly of a plurality of mills in a vertical row for grinding of material to different degrees of fineness according to the number of mills and the setting of the rolls in each mill, and which structure enables the use of one or more of the mills as desired without disassembling a battery of the same.

Heretofore mills of the general type herein considered have been so constructed as to make adjustment of the rolls and trammimg thereof a very difficult and arduous task that required the dismantling of the mills. Also the spacing of the rolls during operation of the mills could not be performed with any degree of accuracy nor could samples of the ground product be easily taken at any point within the mills during operation thereof.

With the present invention all of the objections are overcome. The rolls can be readily inspected and replaced if desired, without completely dismantling the mill. Trammimg of the rolls is quickly accomplished and accurate changing of the spacing between the rolls to known distances can be accomplished almost instantaneously. Furthermore the operator can quickly take a sample of the product being ground at

any desired point within a mill without stopping the mill or mills and without in any way interfering with the normal operation of the mill or mills.

5. Other objects and advantages will appear in the detailed description and in the drawings.

Fig. 1 is a top plan view of one of the mills.

Fig. 2 is a side elevational view of one of the mills with portions broken away and in section.

10. Fig. 3 is an enlarged and elevational view of one of the mills.

Fig. 4 is a vertical sectional view taken along line 4—4 of Fig. 2.

Fig. 5 is an enlarged fragmentary sectional view 15 taken along line 5—5 of Fig. 3.

Fig. 6 is a fragmentary sectional view taken through a portion of a scraper adjusting means.

Fig. 7 is a diagrammatic view of a plurality of mills in a vertical row.

20. In detail each grinding mill of the present invention comprises a housing that is horizontally divided into an upper portion and a lower portion, which portions are removably secured together by bolts or the like.

25. The upper portion of each housing comprises opposed vertically disposed end plates 1, 2. Horizontally elongated side walls 3, 4 extend between said end plates 1, 2 the said side walls forming the front upper side and the rear upper side of the housing. Walls 3, 4 are formed with flanges 5 at their ends for bolting said walls to the upper end plates 1, 2. These walls 3, 4 extend divergently downwardly from their upper edges and have horizontal coplanar oppositely outwardly

30. 35. extending flanges 6 formed along their upper edges, and similar horizontal, coplanar oppositely outwardly extending flanges 7 along their lower edges (Fig. 4). The end plates 1, 2 have flanges 8 along their upper edges that are coplanar with flanges 6, and flanges 9 along the lower edges of said end plates are coplanar with the flanges 7, except that the lower edges are recessed at spaced points for the shafts of the rolls as will later be explained more in detail.

40. 45. The lower portion of each housing comprises opposite end plates 10, 11 that are flanged along their upper edges at 12 for bolting to flanges 9 that are formed along the lower edges of the upper end plates 1, 2. These lower end plates 10, 11 are also flanged at 13 along their lower edges for bolting to any desired discharge hopper or for bolting to the flanges 8 of the upper portion of another mill that may be therebelow, as occurs when a battery of the mills is used to obtain different grinding stages.

Extending between lower end plates 10, 11, are lower horizontally elongated side walls 15, 16 that are flanged at their ends as at 17 for bolting of said side walls to end plates 10, 11, while horizontal flanges 18 extend longitudinally of the said walls 15, 16 along their upper edges for bolting to the lower flanges 7 of the upper side walls 3, 4. Flanges 19 along the lower edges of the lower walls are for bolting to the upper flanges 6 of walls 3, 4. The lower walls 15, 16 extend convergently downwardly from their upper edges.

It is pertinent to note that the coplanar flanges 6, 8 around the upper edges of the housing are adapted to be bolted to flanges 13, 19 around the lower edges of another identical housing whereby a vertical row of mills as indicated in Fig. 7 may be assembled.

The adjacent lower and upper edges of the end plates 1, 10 and 2, 11 are complementarily recessed at spaced points therealong to provide a pair of horizontally spaced openings 21, 22 along the junctures between said end plates for passing the opposite ends of the shafts 23, 24 at the ends of the grinding rolls 25, 26 therethrough.

The lower end plates 10, 11 are respectively provided with the lower halves 27 of bearings for the end shafts 24 of roll 26, this roll being stationary relative to the housing insofar as any radial movement thereof is concerned. The upper half 28 of each bearing is removably secured to the lower half 27 by bolts. It is to be noted that rolls 25, 26 are horizontally disposed in side by side relationship and the lower half 27 of the bearings for roll 26 face generally in the direction of the roll 25, the line of division between the upper and lower halves of the bearings being along the line 29 (Fig. 3). Thus the radial lateral thrust of the lower roll is adequately taken by the lower halves 27 of the bearings supporting roll 25, which lower halves 27 are in turn bolted to supports 30 integral with the lower end plates 10, 11.

The other roll 25 of the pair is supported at its ends in bearings carried by the upwardly extending short arms 31 of cranks that are pivotally supported on the lower end plates 10, 11 by coaxial pivots 32.

The bearing on each of said arms is divided into a lower half 33, that is similar to the lower half 27, and an upper half 34 is removably secured to said lower half by bolts. The line of division 35 between halves 34, 33 is inclined oppositely to line 29 so that the lower halves 33 will adequately take the lateral radial thrust of the roll 25 when material is being ground between the rolls. Each pivot 32 extends eccentrically through a rotatably adjustable bearing 132 releasably clamped between the head of pivot 32 and the end plate into which the pivot is threaded (Figs. 2, 3).

The long arms 40 of the cranks carrying the roll 25 extend horizontally and parallel in direction outwardly of the front side of the housing, and each of said arms is pivotally connected at 41 (Fig. 3) adjacent its outer end to the lower end of a vertically upwardly extending rod 42, the upper end of which extends through an aperture in the closed upper end of the upper portion 43 of a cylindrical spring housing. The lower open end of said portion 43 telescopically receives the open upper end of a lower cylindrical portion 44, and the lower closed end of this portion 44 is apertured for slidably passing rod 42 therethrough. Said lower end is also supported on a support 45 that is rigid with the main housing of the mill 75 that is rigid with the main housing of the mill 75

(Fig. 3). Between the closed ends of each spring housing is a coil spring 46 that reacts against the said ends thereby tending to yieldably move rod 42 and the outer end of the long crank arm 40 upwardly when said spring is compressed. A nut 47 on the upper end of rod 42 above the closed upper end of said portion 43 of the spring housing is for adjusting the tension on the spring, assuming the arm 40 is blocked from being freely elevated, as is the case, and as will be explained.

It is to be understood that there is one of the above spring housings and springs therein adjacent each end of the mill, and these are identical, and an identical rod 42 connected with each of the arms 40 at said opposite ends of the mill extends through each spring 46. Great care is taken to make each pair of springs 46 on each mill exactly the same so they will provide equal tension upon being equally compressed.

The outer ends of crank arms 40 adjacent the pivots 41 are secured against being pulled upwardly by engagement between the flat upper end of a vertically adjustable cam adjusting pin 64 on each of such ends and the flat lower side 48 of an eccentric cam sleeve 49 that is rotatably supported on an eccentric cam 50 that in turn is secured on each end of an eccentric cam shaft 52 (Figs. 2, 3).

The shaft 52 is journaled in bearings rigid with the main housing of the mill, and a manually actuated lever 53 is secured at one end to said shaft 52 for rotating the same.

Adjacent lever 53 is a quadrant 54 (Figs. 3, 5) formed with a pair of rows of openings 55 therein, and said lever carries a pair of taper ended pins 56 (Fig. 5) for the openings of each row. Springs 57 are provided for tending to urge the pins 56 into whichever of holes 55 is adapted to receive one or the other of the pins for locking the cam shaft in whatever position is desired. Knurled knobs 58 on the pins can be grasped by the finger for withdrawing them to permit rotation of the lever.

Returning to the spring housings 43, 44 it is seen that calibrations or graduations 59 are on the inner lower portion 44 to enable the operator to adjust each of the two housings so as to produce absolutely equal tension on the springs, and which tension, as seen from the foregoing description, is transmitted to the cam contact sleeves 49. Thus upon a predetermined pressure between the rolls 25, 26 the latter may open up against the tension of springs 46, but the spacing between the rolls is determined by the degree of rotation of the eccentric cam shaft 52 in one direction or the other. This spacing must or should be extremely accurate so the operator can regulate the spacing to say at least .001 of an inch. The double row of openings 55 enables such adjustment, since the holes in the rows are in staggered relationship. The use of the taper pins for holding the lever in the desired position insures a positive lock that cannot accidentally be released, yet one that can be readily released by the operator when desired.

It is to be noted that an opening 60 on the quadrant is somewhat removed from the openings 55. This opening is used when the operator desires to fully open the rolls so the material will freely pass therebetween. An opening 61 between opening 60 and the row of openings 55 may be used where the mill is one in a series or battery, and it is desired that the previously ground material pass between the rolls without further grinding thereof (Figs. 3).

As best seen in Fig. 3 a pair of relatively adjustable stop bolts 62 are provided, these being carried by bracket members 63 on the roll bearings, and which pair of bolts may be at each of the opposite ends of the mill. The purpose of these bolts is to prevent any possible contact between the rolls irrespective of rotation of the eccentric cam shaft. Engagement between the bolts will occur before the rolls can strike each other.

Below each of the rolls 25, 26 is an elongated scraper blade 65 (Figs. 4, 6). The opposite ends of the blade below roll 25 are each carried on an eccentric pin 66 of an eccentric shaft 67 that extends through a bearing 68 that in turn threadedly extends through the lower side wall of the housing. Two such eccentric shafts extend through the side wall 15 and two through wall 16. Each mounting for each scraper is the same so only one will be described in detail.

Each shaft 67 has a flange 69 that engages the inner end of bearing 68 and a nut 70 outside the housing wall together with flange 69 locks the bearing 68 against axial movement, but upon releasing the nut 70 the bearing 68 can be moved axially thereof, to carry the blade 65 in the same direction.

The outer end of the eccentric shaft 67 is threaded for a nut 71. This nut 71 tightens the shaft against rotation, but when the nut 71 is loosened, the shaft 67 can be rotated thereby elevating or lowering the scraper blade. Once an adjustment of the scraper blades is accurately made (the latter does not contact the rolls), it seldom requires change, but the eccentric shafts enable any desired adjustment to be quickly and accurately made.

The slanted upper side walls 3, 4 are formed with rectangular openings 73 closed by doors 74 that are releasably held closed by rotary spring urged catcher 75. These doors are so formed that they offer no ledges or the like for the accumulation of material. The central portions of the doors are formed to progressively extend through said openings 73 from the upper to lower edges of the openings so that the said central portions will extend over the lower edges of the openings thereby preventing any material from lodging on said lower edges.

Openings 76 are formed in each of the lower side walls 15, 16, which openings are similar to the openings 73. Doors 77 close said openings, and here again the central portions of said doors extend through the openings to cover the lower edges of the latter and to prevent the lodgement of material around said doors. Spring latches 78 releasably hold the lower doors closed.

These doors 74, 77 are adapted to be completely removed from the mill housing, having lips 80 that extend over the inner lower marginal portions of the door opening, while the latches 75, 78 hold the outer flanges 81 against the outer sides of the door openings. The lower openings provide access to below the rolls 25, 26 so that samples of the material being ground can be taken at any time without stopping the mill.

The upper openings provide access to the space above the rolls, and if an examination of the material from below the rollers shows that the rolls are not parallel, and the material is being ground finer at one end than the other, the operator can readily adjust the rolls to position them in proper parallel relationship, this trammimg being done through the upper openings without disassembling the mill.

A feed chute extending longitudinally of the rolls is adapted and feeds material to between the said rolls throughout their length. This chute has convergently downwardly extending sides 82 and end walls that are provided with outwardly extending flanges 83 (Fig. 4) at the upper edges thereof. The upper edges of the side walls 3, 4 and end walls 1, 2 are recessed to receive flanges 83.

Between the ends of the chute sides and at points corresponding substantially to the openings 73, the sides of the fixed chute are cut away and convergently downwardly extending plates 84 on the inner sides of the chutes extend across said cut away portions. These plates 84 are hinged along their upper edges at 85 to the main fixed chute above the cut away portions, and the said plates 84 are of a length that permits them to be swung upwardly and out of the way while the operator is trammimg the rolls. This structure also prevents lodgment of material anywhere within the chute.

Above the mill is any suitable feed device, such as a feed hopper having a passageway 86 that leads to a distributor roll 87. This roll is connected with any suitable source of power for rotating it under a vertically adjustable feed gate 88, the control of which is by means of exposed screws 89 at the ends of the gate, and which screws are at the front side 90 of the feed device. The said gate is yieldable in a direction away from the roller against the tension of spring 91 around the screws, but the gate is held by the screws against movement toward the roll unless the thumb nuts 92 on said screws are rotated to release the screws.

The lower end of the feed device is flanged to enable securement of said device on the flanges around the upper edge of the mill housing.

The roll shafts 23, 24 at the ends thereof opposite the ends adjacent the quadrant, are provided with gears 93, 94 that are in mesh with each other and the shaft 24 at the end adjacent said quadrant may carry a pulley 95 for connecting said shaft with any suitable source of power. A sprocket gear 96 on shaft 24 may also connect the same with the shaft of the distributor roll 87 by means of a chain 93.

As seen in Fig. 7 the present structure enables the assembly of a mill having as many stages as desired. In some instances it may be found desirable to use only a one stage mill, in which case only one unit need be used, the others being rendered inoperative by opening the rolls to their fullest spacing.

In still other instances it may be desirable to have the rolls of progressively closer spacing commencing with the rolls of the top unit. This is readily done by merely swinging the adjusting lever 53 to the proper position as indicated by the numerals or indicia identifying the openings 55 in the quadrant. Any desired spacing of the rolls can be done while the mill is in operation.

Should it be found necessary to replace rolls, this is readily done by removing the upper end plates of the unit so as to permit such removal of the rolls and replacement by others.

No material will lodge in the mill because all surfaces where there might be a lodgment slant downwardly and are, therefore, self cleansing.

The flat engaging surfaces between the contact sleeves 49 and the cam adjusting pins 47 substantially eliminate any wear that might otherwise prevent the accurate spacing of the

rolls and the springs 46 provide for a uniform tension of any desired degree against the roll 25.

It is to be noted that the aligned openings in the ends of the mill housing are horizontally elongated to permit adjustment of roll 25. These openings as well as the openings 22 have dust seals 99 of felt or the like closing them at all times so no dust will escape from the mill. When desired the entire upper half of the mill housing can be removed.

Tramming of the rolls is quickly accomplished by rotation of the eccentric sleeves 132 as desired.

Also it is important to note that the openings 55 in the quadrant are identified by numerals 155 that designate the spacing of the rolls in thousandths of an inch, thus enabling the operator to quickly provide the desired exact spacing of known value and to change from one exact known spacing to another exact and known spacing.

It is to be understood that the invention is not to be restricted to the precise details shown and described, inasmuch as the detailed drawings and description are merely illustrative of a preferred form of the invention.

We claim:

1. A grinding mill comprising a pair of horizontally elongated grinding rolls, a housing enclosing said rolls, stationary bearings carried by said housing for rotatably supporting one of said rolls, a pair of movable bearings for rotatably supporting the opposite ends of the other roll of said pair, a bell-crank pivotally secured to said housing and provided with generally vertically extending arm for receiving one of said bearings at the outer end thereof, the other arm of said bell-crank being generally horizontal, eccentric means directly engageable with the outer end of said other arm for swinging the same to adjust the spacing between said rolls, said last mentioned means comprising a sleeve having a planar outer surface for engaging the outer end of said arm and an eccentric element supported for oscillation within said sleeve for so swinging said arm.

2. A grinding mill comprising a pair of horizontally elongated grinding rolls, a housing enclosing said rolls, stationary bearings carried by said housing for rotatably supporting one of said rolls, a pair of movable bearings for rotatably supporting the opposite ends of the other roll of said pair, a bell-crank pivotally secured to said housing and provided with generally vertically extending arm for receiving one of said bearings at the outer end thereof, the other arm of said

bell-crank being generally horizontal, eccentric means directly engageable with the outer end of said other arm for swinging the same to adjust the spacing between said rolls, said last mentioned means comprising a sleeve having a planar outer surface for engaging the outer end of said arm and an eccentric element supported for oscillation within said sleeve for so swinging said arm, yieldable means connected with said other arm at a point between said eccentric means and the pivot of said bell-crank for yieldably resisting movement of said first mentioned arm in a direction away from said one roll.
